LOOM TEMPLE

Fredric E. Douglas, Hopedale, Mass., assignor to
Draper Corporation, Hopedale, Mass., a corporation of Maine

Application January 27, 1936, Serial No. 60,899

6 Claims. (Cl. 139—295)

The present invention pertains to loom temples, and has more particular reference to such temples having a plurality of fabric gripping rollers supported in and housed by a temple pod and cap.

The prior commercial form of temple of the type mentioned comprises a pod having a plurality of parallel fabric gripping rollers therein, and a cap detachably secured to the pod, the cap containing a fabric gripping roller which is yieldingly pressed toward the rollers in the pod. The cap-contained roller is mounted for floating movement, as by being mounted on a roll pin which is loosely received in open-ended slots in the cap. A single elongated spring, extending lengthwise of the cap, acts on the roll pin through the medium of plungers engaging the ends of the roll pin.

The prior temple, as just described, was inconvenient to assemble and dismantle because the open-ended slots allowed the roll pin and roller to fall out of the cap whenever the latter was detached from the temple. The present invention has for one of its objects the provision in a temple of the type described of a hanger member connected at its lower end to the roll pin and detachably connected at its upper end to the roller-actuating spring, whereby the roll pin and roller are detachably secured in the cap.

A further object of the invention is to provide a temple cap having a spring-pressed fabric gripping roller, a roll pin loosely supported in open-ended slots in the cap, and a hanger member detachably securing the roll pin to the spring.

I have devised and herein disclose, two embodiments of the invention. In both said embodiments, a hanger member is provided at each end of the temple cap and each hanger member is apertured at its lower end to receive an end of the roll pin. In one embodiment, the elongated spring is split, or slotted, at each end, and each hanger member is notched at its upper end to fit into the proper slot in the spring. In this embodiment the hanger members serve not only to detachably secure the roll pin in the cap but also to transmit pressure from the spring to the roll pin.

In the other embodiment herein disclosed, the roller and roll pin are yieldingly pressed downwardly by an elongated spring acting through plungers slidably mounted in the end walls of the cap. Hanger members are provided at opposite ends of the cap as in the first embodiment, but the means of detachably securing the hanger members to the spring is different in that each

member is provided with a comparatively large aperture through which the spring extends.

The said embodiments are illustrated on the accompanying drawing, of which:

Fig. 1 is a plan view of a temple constituting 5 the first embodiment above mentioned;

Fig. 2 is a view of the rear face of the temple of Fig. 1, with the cap partly broken away and appearing in section;

Fig. 3 is a view in cross-section taken approximately on line 3—3, Fig. 2;

Fig. 4 is a view in cross-section taken approximately on line 4—4, Fig. 5; and

Fig. 5 is a view similar to Fig. 2 but showing the temple comprising the second embodiment 15 above mentioned.

The temple of Figs. 1—3 includes the housing 1 which is adapted to be mounted so as to extend lengthwise of the cloth C being woven. A bar 2 is slidably mounted in the housing in the usual 20 manner and is provided with a laterally extending head wherein fabric gripping rollers are mounted. The head includes a pod 3 which in the present instance is formed integrally with the bar 2. The head also includes a cap 4 which is 25 comprised of an elongated body detachably secured to the pod. The cap is shown as being secured to the pod by means of a screw 5 and held in proper position by a tongue and groove 6.

The pod is shown as having two parallel fabric gripping rollers 7, 7. The pod has parallel grooves in which the rollers are received. The rollers are rotatably mounted on fixed roll pins 8, 8 in the usual manner. The particular rollers shown, being designed for use with fine fabrics, are comprised of a wood body covered with leather. It will be noted that the rollers are spaced apart longitudinally of the cloth a distance which is less than their diameters.

The cap 4 has front and rear fabric guiding bars 9 and 10, respectively, and end walls 11 and 12. The end walls are slotted vertically as at 13, Fig. 2, and the slots are open at their lower ends. A roll pin 14 is loosely positioned 45 in the slots for floating movement. That is, the roll pin is free in the slots to move bodily up and down and horizontally in a direction longitudinally of the cloth. The roll pin is, however, prevented from rotating, it being provided with a 50 flattened portion 15 of greater height than the width of the slot in which it is positioned. It will be apparent that the slots 13 must be open at one end to permit insertion and removal of the roll pin 14. A further reason for making the 55

slots open-ended is to facilitate their formation by commercial manufacturing methods.

A third fabric gripping roller 16 is rotatably mounted on the roll pin 14, this roller extending parallel to the rollers 7, 7 and being yieldingly pressed toward the latter to grip the fabric there-between. Spring means for yieldingly pressing the upper roller downwardly is herein comprised of an elongated spring 17 which is carried by the cap and extends longitudinally thereof directly above the roller 16. The spring is held stationary at a point intermediate its ends by a cross bar 18 of the cap, while the ends of the spring are free to flex up and down. The spring 17 is formed of flat material and is split, or slotted, longitudinally as at 19 for a substantial distance in from each end, for a purpose to be described.

The ends of the spring 17 are operatively associated with the roll pin 14 to yieldingly press the roll pin and roller downwardly toward the rollers 7, 7, while still permitting floating movement of the roller 16. The roll pin is also detachably connected with the spring.

In the embodiment of Figs. 1-3 both of the said functions are performed by a pair of hanger members 20, 20. One hanger member is positioned at each end of the cap and the two members are preferably identical. Each hanger member is apertured at its lower end to receive an end of the roll pin, whereby the members are pivotally connected to the pin, as more clearly shown by Fig. 2. The upper end of each hanger member is detachably connected to an end of the spring 17. To this end, each member is notched adjacent its upper end, see Fig. 3, and the notched portion is positioned in a slot 19. The spring thus acts through the hanger members to depress the roller 16, while the hanger members also serve to retain the roll pin and roller within the cap whenever the latter is removed from the temple.

The embodiment shown by Figs. 4 and 5 of the drawing may employ a pod 21 with rollers 22, 22 therein, which may be identically like the corresponding parts of the temple above described. The temple cap 23 is similar to the cap 4 in that it has the same slotted end walls, roll pin 24 and roller 25 and the same cross bar for holding the spring 26. The spring is elongated and extends lengthwise of the cap, but its ends need not be slotted. This spring is operatively associated with the roll pin 24 through plungers 27, 27 which are slidably mounted in the end walls of the cap. The ends of the spring engage and depress the plungers to thereby yieldingly press the roller 25 downwardly while still permitting floating movement of the latter as above described in connection with the first embodiment.

60 The hanger members 28, 28 of Figs. 4 and 5 are pivotally connected at their lower ends to the roll pin 24 as above. The manner of detachably connecting the hanger members to the ends of the spring is, however, somewhat different. In 65 the present embodiment, the hanger members are apertured at their upper ends, as at 29, and the ends of the spring merely pass through these apertures. Thus, in this embodiment the hanger members perform only the function of retaining the roll pin and roller in the cap when the latter is removed from the temple.

Having fully disclosed the preferred embodiments of my invention, I claim:

75 1. A loom temple comprising a pod having a plurality of fabric gripping rollers therein, a cap

detachably secured to said pod, a floating roll pin and fabric gripping roller loosely mounted in said cap, a single flat spring extending lengthwise of said cap, said spring intermediate its ends being held stationary by said cap and the ends of said spring being operatively associated with the ends of said roll pin to yieldingly urge the roll pin and the last said roller toward the rollers in said pod, a hanger member at each end of said roll pin, each hanger member being apertured at its lower end to receive said roll pin, and means detachably securing the upper end of each hanger member to an end of said spring. 5

2. A loom temple comprising a pod having a plurality of fabric gripping rollers therein, a cap 15 detachably secured to said pod, said cap having end walls, a roll pin loosely supported in open-ended slots in said walls, a fabric gripping roller rotatably mounted on said roll pin, a single elongated spring extending lengthwise of said cap 20 directly over said roll pin, a portion of said spring intermediate the ends thereof being held stationary by said cap and the ends of said spring being operatively associated with said roll pin to yieldingly urge the latter toward the rollers in 25 said pod, and a connecting member at each end of said cap and separate therefrom, each said member being pivotally connected at its lower end to said roll pin and detachably connected at its upper end to an end of said spring. 30

3. As an article of manufacture, a temple cap comprising an elongated body having end walls, a roll pin extending lengthwise of said body and loosely supported for floating movement in open-ended slots in said end walls, a fabric gripping 35 roller mounted on said pin, spring means acting on said roll pin to urge the latter in a predetermined direction, said means including a single elongated spring extending lengthwise of said body and supported thereby, and means detachably securing said roll pin and roller in said cap, the last said means being comprised of a hanger member at each end of said roll pin, each hanger member being pivotally connected at one end to said roll pin and detachably connected at its other 45 end to an end of said spring.

4. As an article of manufacture, a temple cap comprising an elongated body having end walls, a roll pin extending lengthwise of said body and loosely supported for floating movement in open-ended slots in said end walls, a fabric gripping roller mounted on said pin, a single flat spring carried by said body generally parallel to said roll pin, means carried by said end walls for transmitting pressure from said spring to said 55 roll pin, and a separate hanger member at each end of said body for detachably securing the ends of said roll pin to said spring. 60

5. As an article of manufacture, a temple cap comprising an elongated body having end walls, 60 a roll pin loosely supported in open-ended slots in said end walls, a fabric gripping roller mounted on said roll pin between said end walls, a single flat spring extending generally lengthwise of said body and supported thereby, the ends of said 65 spring being slotted longitudinally thereof, and a hanger member at each end of said body, each of said members being apertured at one end to receive an end of said roll pin, the other end of each of said members being notched and the 70 notch thereof being positioned in one of the slots in said spring.

6. As an article of manufacture, a temple cap comprising an elongated body having end walls, a roll pin loosely supported in open-ended slots 75

in said end walls, a fabric gripping roller mounted on said roll pin between said end walls, a single flat spring extending generally lengthwise of said body and supported thereby, the ends of said spring being slotted longitudinally thereof, and a member at each end of said body for transmitting pressure from said spring to said roll

pin and for detachably securing the latter to said spring, each said member being pivotally connected at one end to said roll pin and each member having at its other end a notched portion engaged in one of the slots in said spring. 5
